UNITED STATES PATENT OFFICE

115,055

DESIGN FOR A FUR CAPE

Harry Soldinger, Edgemere, Long Island, N. Y.

Application April 27, 1939, Serial No. 84,592

Term of patent 14 years

To all whom it may concern:

Be it known that I, Harry Soldinger, a citizen of the United States, residing in Edgemere, Long Island, in the county of Queens and State of New York, have invented a new, original, and ornamental Design for a Fur Cape, of which the following is a specification, reference being had to the accompanying drawing, forming part thereof.

In the drawing:

I claim:

The ornamental design for a fur cape, as shown.

HARRY SOLDINGER.
